UNITED STATES PATENT OFFICE.

JOSEPH W. FEE AND DOUGLAS MOREY, OF BRISTOL, RHODE ISLAND.

SHOE-LAST-SECURING MEANS.

1,295,467.

Specification of Letters Patent. Patented Feb. 25, 1919.

Application filed August 16, 1918. Serial No. 250,111.

To all whom it may concern:

Be it known that we, JOSEPH W. FEE and DOUGLAS MOREY, citizens of the United States, residing at Bristol, in the county of Bristol and State of Rhode Island, have invented a new and useful Improvement in Shoe-Last-Securing Means, of which the following is a specification.

This invention relates to certain new and useful improvements in shoe last securing means and pertains more particularly to means for securing the lasts to the shoe bar.

Heretofore, and especially in rubber shoe manufacture, the last has a pair of holes bored therein and the shoe bar has a corresponding number of pins for each last. The shoe bar commonly carries a number of lasts, depending upon the size of the shoe to be made. After completing the work on the shoe the operative sets the lasts upon the pins of the shoe bar. The bar with the last and shoe is subjected to proper temperature to cure the same. This pin and hole securing means has been found to be objectionable, since the pins are frequently bent or broken and the holes in the last become worn from frequent use, and consequently in placing the shoe bar in the curing oven the lasts frequently slip off of the pins and spoil the work in addition to involving a loss of time and trouble in replacing the lasts on the bar.

The present invention therefore aims to overcome the objections noted and briefly resides in the provision of a spring or equivalent clasp or clip, or other device which is rigidly secured to the last and which snaps over the shoe bar, thereby not only eliminating the formation of holes in the last with consequent weakening of same but to the contrary preserving full strength of the last with the addition of such reinforcement as the clip or clasp can be said to afford.

The invention also possesses the additional advantage that the shoe bar has its full strength preserved in that it is not necessary to bore holes in the same for the securement of the pins above mentioned.

Further and other objects will be later set forth and of themselves manifested in the course of the following description.

In the drawings—

Figure 1 is a perspective view of the invention applied to a last, the latter being shown in fragment.

Fig. 2 is a side elevation showing the shoe bar in section.

Fig. 3 is a similar view of a modification, and

Fig. 4 is a bottom plan view of Fig. 3.

In proceeding in accordance with the present invention a clasp or clip is provided having a flat base 1 rigidly secured by screws 2 to the flat end of the neck of a last L. One end of the clasp, which latter is formed of a strip of spring metal, is bent at 3 right angles at 3, and then extended inwardly at 4 to lie parallel to base 1 while the other end of the strip is curved at 5 to lie at substantially right angles to base 1 and has its end rolled or curled or beaded at 6 so as to provide a finger grip and also to allow the clasp to be easily snapped over and removed from the shoe bar B. As shown in Fig. 2 the jaw provided by the parts 3 and 4 is first slipped over one side edge of the shoe bar with the last occupying the position shown in dotted lines, following which the last is forced downwardly to cause the bead 6 to ride over and snap under the opposite side edge of the shoe bar. The last is thus held in a secure manner and can be removed by simply pressing with the fingers against the bead 6 to move the latter out of engagement with the under face of the shoe bar whereupon the last can be swung to the dotted line position shown in Fig. 2 and then completely removed.

Referring to Figs. 3 and 4 it will be seen that the shoe bar B is provided with pairs of aligned notches or cut-outs 7 in its opposite side edge. These notches are arranged at spaced predetermined intervals throughout the effective length of the shoe bar so that the lasts will be properly located at desired spaced intervals along the length of the shoe bar. A slightly modified form of the clasp is employed in Figs. 3 and 4 having a base 1' and parts 3'-4' corresponding to the parts 3 and 4 in the preferred form of the invention, while the other end of the metal strip is turned at direct right angles at 8 and is formed with an inturned terminal 10 forming a beveled nose or catch proper which is adapted to snap over the bar B.

In the form shown in Figs. 3 and 4, it will be apparent that the bases of the clips are of less length than in instances where the

shoe bar is not notched, as shown in Fig. 2, so that in the modified form the clips will engage the end walls formed by the cut-outs 7, and thus be held against longitudinal movement along the length of the shoe bar.

Having thus described our invention, what we claim as new and desire to secure by Letters Patent is—

1. In combination with a shoe bar, and a last, a spring clip rigidly secured to the top end of the last neck and having a pair of jaws formed by bending its ends, said jaws being formed so as to snap over the bar and to engage over the opposite side edges thereof.
2. In combination with a shoe bar, and a last, a spring clip rigidly secured to the last and having means on its ends to engage over opposite side edges of the bar.
3. In combination with a shoe bar, and a last, spring means carried by the last for removable engagement with opposite side edges of the bar.
4. In combination with a shoe bar, and a last, means carried by the last for engagement with opposite side edges of the bar to allow the last to be secured to and removed from the bar.
5. In combination with a shoe bar, and a last, means formed to snap over opposite side edges of the bar to removably secure the last thereto.

6. In combination with a shoe bar having a series of pairs of cut-outs formed in its opposite side edges, a last, and means carried by the last to engage over opposite side edges of the bar and in said cut-outs.

7. In combination with a shoe bar having a series of pairs of cut-outs formed in its opposite side edges, a last, and a spring clip secured to the last and having jaws on its ends to engage over the opposite side edges of the bar in said cut-outs, and to engage the end walls formed by the cut-outs to prevent longitudinal movement of the last along the length of the bar.

8. In combination with a shoe bar having a series of pairs of cut-outs formed in its opposite side edges, a last, and means to secure the last to the bar engageable in said cut-outs.

9. In combination with a shoe bar having flat unobstructed faces, a last, and means engageable with opposite side edges of the bar to removably secure the last thereto.

In testimony whereof we have signed our names to this specification in the presence of two subscribing witnesses.

JOSEPH W. FEE.
DOUGLAS MOREY.
